SAFE AND VAULT DOOR AND FRAME AND
METHOD OF MAKING SAMEArthur H. Lambden, Galt, Ontario, Canada, as-
signor to The Goldie McCulloch Company
Limited, Galt, Ontario, CanadaApplication June 13, 1932, Serial No. 616,887
In Canada October 15, 1931

6 Claims. (Cl. 29—148)

It has been usual to construct steel vault and safe doors by either of two methods. The older of these methods was to form a laminated door by securing together a series of plates by bolts or screws. The method most commonly in use in making doors at the present time is to form a recessed cast steel framework, the recess in which is filled up with steel plate or other filler. The door frames are also usually formed of cast steel.

10 The present construction, while satisfactory in use, is very expensive to make as so many different sizes are required, and each different size involves first making the necessary patterns to enable the castings to be made.

15 My object therefore is to devise a construction, which, while possessing the strength of the cast steel construction, may be made without requiring the provision of the expensive patterns heretofore required, thus materially reducing the cost of the 20 doors and frames.

I attain my object by building up the door frame of steel bars previously cut to the proper size and shape and welding the parts together, and then filling the recess thus formed with a suitable 25 torch and drill resistant material.

The construction is hereinafter more particularly described and illustrated in the accompanying drawing in which

Fig. 1 is a cross section through a vault door 30 and frame constructed in accordance with my invention, the door being in open position;

Fig. 2 an elevation of the door and frame, partly broken away, the door also being in open position;

35 Fig. 3 a cross section through the door and frame with the door closed, and on a larger scale; and

Fig. 4 a vertical section through the door and frame with the door closed.

40 In the drawing like numerals of reference indicate corresponding parts in the different figures.

The door is formed of two sections secured together, the main protective section A and the bolt carrying section B.

45 The main section is formed as a framework comprising four members 1, forming sides and ends, which have been previously cut to the desired length and edged and shaped to present the required bevel, and are also preferably ground 50 and polished. The ends of the parts are then prepared for welding and the ends then welded together to form a rectangular door hoop, the lines of weld being indicated by the dotted lines 15.

55 The bolt carrying section B is similarly con-

structed comprising four members 3, also forming sides and ends, which have been previously cut to the desired length, edged and shaped to present the required bevel. The bolt holes are drilled in the parts before assembly and the parts 60 are also drilled and countersunk for screw fastenings. The parts may also be suitably ground and polished. The ends of the bolt carrying section parts are then prepared for welding, and the ends are then welded together to form a rectangular bolt frame hoop, the lines of weld being indicated by the dotted lines 16.

The necessary holes are then drilled in the door hoop to correspond with the countersunk 70 holes in the bolt frame for the fastening screws. The bolt frame hoop is then fitted within the door hoop and secured thereto by screws 5 and will also usually be welded thereto. A lock plate 6 which may be of one or more plies, is then fitted

75 in the door assembly in front of the bolt holes and welded in place, the line of weld being indicated by the dotted line 17. The recess in front of the plate 6 is then filled in with a suitable

filling 7, preferably such as to withstand high 80 temperatures and drilling, and finally a heavy plate 8 is fitted in the mouth of the recess and welded to the door hoop. A covering plate 11 of suitably polished or finished steel is then secured in front of the frame and plate, preferably

85 by welding.

12 indicates the locking bolts, which are supported in any convenient manner and 2 the slides for operating the same, but it will be understood that the arrangement and operation of the bolts and operating and locking means therefore may 90 be varied as may be required to suit individual cases and form no part of the present invention and therefore they need not be further described.

The door frame or jamb is constructed in a somewhat similar manner. First four separate 95 steel bars 4 to form the sides and ends are cut to the desired length, edged and shaped to present the required bevel. They are then preferably ground and polished. After the ends of these members are prepared for welding, the 100 welding is effected to form a rectangular jamb hoop.

An angle hoop is then formed comprising four separate pieces three of them 10 being of angle steel and one 10^a of flat stock which are suitably prepared and welded together to form a rectangular angle hoop. The jamb hoop is then inserted in the angle hoop and joined thereto by a continuous weld to form a solid unit, the line of weld being indicated by the dotted line 19. The 110

angular space between the angle hoop and jamb hoop is filled with a suitable filling 13 having high torch and drill resisting qualities, for example, concrete reinforced with chrome rods. Behind this combined construction is secured the stop hoop 14, which forms a stop against which the inner edge of the ring A may abut when the door is in closed position. This hoop 14 may also be formed of separate parts welded together at 10 the ends.

It will be seen that according to this method of construction it is comparatively simple to construct a door or frame of any size or proportion without the use of expensive patterns as required 15 in a moulding process, and further that an extremely strong construction is obtained.

What I claim as my invention is:

1. In a vault or safe door, a rectangular metal frame comprising side members and end members welded together at the corners of the frame; and a metal bolt frame comprising side members and end members welded together at the corners of the frame, said bolt frame being fitted within the first mentioned frame with their adjacent 25 surfaces partially overlapping and secured to one another.

2. In a vault or safe door, a rectangular metal frame comprising side members and end members welded together at the corners of the frame; 30 a metal bolt frame comprising side members and end members welded together at the corners of the frame, said bolt frame being fitted within the first mentioned frame with their adjacent surfaces partially overlapping and secured to one another; a lock plate spaced from the front of 35 said first mentioned frame to provide a recess in front thereof; a protective filling within the re-

cess; and a cover plate welded to the forward edge of said first mentioned frame.

3. In a vault or safe door, the combination of a metal rectangular frame; a separately formed metal bolt frame fitted within the rectangular frame with their adjacent surfaces partially overlapping and secured to one another; and a protective filling in said rectangular frame.

4. In a vault or safe door, a metal door frame formed of bar material having its ends welded together; and a separately formed bolt frame also of bar material with ends welded together, the edges of said last mentioned frame partially overlapping the inside of said first mentioned frame and secured thereto.

5. In a vault or safe door, a metal door frame having inclined walls formed of bar material having its ends welded together; and a separately formed bolt frame also formed of inclined walls and formed of bar material with ends welded together, said last mentioned frame being fitted within the first mentioned frame with their adjacent surfaces partially overlapping, said overlapping portions being secured to one another.

6. A process for making rectangular vault or safe doors or frames which comprises forming the sides and ends of a hollow door frame from separate pieces of bar metal, and welding together the ends of the bars, similarly forming a 105 hollow bolt frame from bar metal and welding together the ends of the bars, fitting the bolt frame within the door frame with the frames in slightly overlapping relation, and securing together said overlapping portions.
